MALCOLM L. COSSITT, OF ALAMEDA, CALIFORNIA, ASSIGNOR TO MANIFOLD IMPRESSIONS CORPORATION, OF CARSON CITY, NEVADA, A CORPORATION OF NEVADA.

MANIFOLDING ATTACHMENT FOR TYPEWRITERS.

Application filed June 20, 1922. Serial No. 569,612.

To all whom it may concern:

Be it known that I, MALCOLM L. COSSITT, a citizen of the United States, residing at Alameda, in the county of Alameda and State of California, have invented certain new and useful Improvements in Manifolding Attachments for Typewriters, of which the following is a specification.

My invention relates to that class of manifolding attachments for typewriters and the like, in which one or more manifolding members are carried by arms mounted on the platen carriage of the machine and are adapted, by the movement of said arms, to be placed in and removed from functional position in the line of type impact; and more especially it relates to a form of such attachments in which the manifolding members are stored within a chambered member and are adapted to be drawn therefrom in successive lengths for association with the carrying arms.

In certain forms of these attachments the carrying arms are associated with a plurality of independently rotatable nested sleeves, and one of the objects of my present invention is to constitute these nested sleeves the chambered member for storing the manifolding members.

Another object of my invention is to provide simple and effective means for placing and holding the manifolding members in proper tension.

Still another object is to provide simple and effective means for the selective operation of the carrying arms whereby one or more of the manifolding members may be moved into and out of functional position.

With these and other objects in view, my invention consists in the novel manifolding attachment for typewriters which I shall now fully describe, by reference to the accompanying drawings, in which—

Fig. 1 is a left hand end elevation of my attachment.

Fig. 2 is a right hand end elevation of the same.

Fig. 3 is a partial section on the line 3—3 of Fig. 1.

1 is the platen carriage of a typewriter, and 2 is the platen.

Secured upon the platen carriage, one near each end, are the bracket arms 3. To the free extremity of the bracket arm 3, at the

left hand end, Fig. 1, is pivoted a bearing member 4 controlled by a spring 5. In the free extremity of this bearing member is fitted a threaded centering shaft 6, set by a screw 7, Fig. 1. In the right hand bracket arm 3 is fitted a threaded centering shaft 8, Figs. 2 and 3, having a knob 9 for turning it—Fig. 3.

Referring now particularly to Fig. 3, there is fitted to the left hand end centering shaft 6 a housing casing 10, the inner end 65 of the casing being centered upon an abutment member 11 which is carried by the innermost sleeve 12 of a nested series of independently rotatable sleeves, the other members of said series being indicated by 12' 70 and 12'' respectively.

The right hand centering shaft 8 is fitted through centering abutments 13 carried by the innermost sleeve 12.

Each sleeve of the nested series has at each 75 end a carrying arm. The arms of the innermost sleeve are designated by 14, those of the middle sleeve by 14' and those of the outer sleeve by 14''. The arms at each end lie in superposed nested relation, and the 80 free extremity of each arm has pivoted to it a ribbon carrying clip-tongue 15, Fig. 1.

Within the housing casing 10 are the spools 16 adapted for independent rotation. These spools carry the manifolding members 17, here shown as ribbons. The ribbons pass from the spools outwardly through suitable slots 18, in the housing casing 10, and are directed within the innermost sleeve to their respective arms at the left hand end. 90 Turning about the bases of these arms the ribbons extend along them to and over the clip-tongues 15 of the arms and thence extend to and are engaged by the clips of the respective arms at the right hand end. The 95 extension of the ribbons between the arms is omitted in Fig. 3, as said arms are shown therein broken. In order to hold the ribbons against pulling strain when under tension, as will be presently described, there is 100 on the face of each left hand arm, as is shown in Figs. 1 and 3, a guide or keeper 19 through which the ribbon passes, and there is also on each arm a flat spring 20 over which the ribbon lies, and by which a 105 pulling strain on the ribbon is frictionally resisted.

Referring to Fig. 3, 21 is a pick up arm

of a springy nature, secured to the centering shaft 8 at the right hand end of the attachment.

Secured to the inner surface of each 5 nested sleeve, and projecting inwardly therefrom are studs 22, the studs of the outer sleeves playing in slots in the inner sleeves, and all extending into the path of revolution of the pick-up arm 21 on the shaft 8.

10 The operation of the device is as follows:

When out of use, all the arms are elevated, and the required sections of manifolding ribbons are drawn out from their chambered spools 16 housed within the nested sleeves, 15 and extend between and are carried by their respective pairs of arms.

When the use of say one ribbon is required, namely, that carried by the foremost arms 14" of the outer sleeve 12", the centering shaft 8 is turned by its knob 9, so that its pick-up arm 21 acting on the first sleeve stud 22 will rotate said sleeve and thus carry the pair of arms 14" of said sleeve and the ribbon extending between them, 25 down to the position shown by the upper dotted lines in Figs. 1 and 2. In this position the ribbon carrying clip tongues 15 contact with and rest upon the platen 2. Further movement, to carry the ribbon down 30 to functional position in the line of type impact, as shown by the lower dotted lines in Figs. 1 and 2, causes the clip tongues sliding upon the platen, to swing outwardly, which movement, by drawing on the length 35 of ribbon section extending along the face of the left hand arm, Fig. 1, has the effect of tightening the ribbon and placing the entire length of functional section between the pair of arms, under proper tension for 40 use.

It will be seen that this tensioning movement is properly resisted by the frictional pressure on the ribbon of the flat spring 20, so that the ribbon spool does not yield to the tension.

If a second ribbon is required, the shaft 8, which, by its previous rotation, in its threaded fitting has moved inwardly far enough to cause its pick up arm to contact with the 50 stud 22 of the second sleeve 12', will now, by its further rotation, swing said sleeve with its arms and ribbon down, as before described, and, likewise, with the third sleeve and its associated parts.

55 As each section of the ribbons is used up, the end of the ribbon is detached from the clip tongues, and a fresh section is drawn out from the storing spool and placed in position between the arms.

60 I claim:

1. A manifolding attachment for typewriters comprising a chambered, rotatable member mounted on the platen carriage of the machine, parallel with the platen; an arm 65 carried at each end of said chambered mem-

ber; and a manifolding member housed within said chambered member and adapted to be drawn out therefrom for association, in successive lengths, with said arms.

2. A manifolding attachment for typewriters comprising a chambered, rotatable member mounted on the platen carriage of the machine, parallel with the platen; an arm carried at each end of said chambered member; a manifolding member housed 75 within said chambered member and adapted to be drawn out therefrom for association, in successive lengths, with said arms, and means for automatically placing said drawn out section under tension as it approaches 80 its functional position in the line of type impact.

3. A manifolding attachment for typewriters comprising a chambered, rotatable member mounted on the platen carriage of the machine, parallel with the platen; an arm carried at each end of said chambered member; a manifolding member housed 85 within said chambered member and adapted to be drawn out therefrom for association, in successive lengths, with said arms; and means for automatically placing said drawn out section under tension as it approaches 90 its functional position in the line of type impact, consisting of pivoted clip tongues on 95 arms and upon which the ribbon section is carried, said tongues bearing on the platen and adapted by their travel thereon to move outwardly.

4. A manifolding attachment for typewriters comprising a chambered, rotatable member mounted on the platen carriage of the machine, parallel with the platen; an arm carried at each end of said chambered member; a manifolding member housed 100 within said chambered member and adapted to be drawn out therefrom for association, in successive lengths, with said arms; means for automatically placing said drawn out section under tension as it approaches 105 its functional position in the line of type impact; and means acting on said ribbon section to resistantly hold it as the tension is applied.

5. A manifolding attachment for typewriters comprising a pair of spaced brackets carried by the platen carriage of the machine; a chambered member rotatably fitted between said brackets, parallel with the platen; an arm carried at each end of said 115 chambered member; and a manifolding member housed within said chambered member and adapted to be drawn out therefrom for association, in successive lengths, with 120 said arms.

6. A manifolding attachment for typewriters comprising a pair of spaced brackets carried by the platen carriage of the machine; a centering shaft carried in each bracket; a chambered member rotatably car- 125 130

ried by said shafts, parallel with the platen; an arm carried at each end of said chambered member; and a manifolding member housed within said chambered member and 5 adapted to be drawn out therefrom for association, in successive lengths, with said arms.

7. A manifolding attachment for typewriters comprising a pair of spaced brackets carried by the platen carriage of the machine; a centering shaft carried by each bracket; a chambered member rotatably carried by said shafts, parallel with the platen; means for rotating one of said centering shafts; coacting elements between said rotatable shaft and said chambered member for turning said member; an arm carried at each end of said chambered member; and a manifolding member housed within said chambered member and adapted to be drawn 20 out therefrom for association in successive lengths, with said arms.

8. A manifold attachment for typewriters comprising a plurality of independently rotatable nested sleeves mounted on the platen carriage of the machine parallel with the platen; an arm carried at each end of said sleeve; a plurality of manifolding members housed within the innermost of said nested sleeves and each adapted to be 25 drawn out therefrom for association in successive lengths with its respective pair of arms; and means for selectively rotating each sleeve.

9. A manifolding attachment for type-

writers comprising a pair of spaced brackets carried by the platen carriage of the machine; a centering shaft carried by each bracket, one of said shafts being threaded in its bearing for rotative and linear movement; a plurality of independently rotatable, nested sleeves carried by said shafts, parallel with the platen; an arm carried at each end of each of said sleeves; a plurality of manifolding members housed within the innermost of said nested sleeves and each 45 adapted to be drawn out therefrom for association in successive lengths with its respective pair of arms; and means for selectively rotating each sleeve consisting of coacting elements on the rotatable and longitudinally 50 moving centering shaft, and said sleeves.

10. A manifolding attachment for typewriters comprising a plurality of independently rotatable, nested sleeves mounted on the platen carriage of the machine, parallel 55 with the platen; an arm carried by each end of each sleeve; a manifolding member carried by and between each pair of arms; a rotatable, longitudinally moving shaft extending into one end of the nested sleeves; a 60 pick-up arm carried by said shaft; and studs on the sleeves projecting into the rotary path of the pick-up arm, whereby said sleeves are selectively rotated.

In testimony whereof I have signed my 65 name to this specification.

MALCOLM L. COSSITT.
